APPARATUS AND METHOD FOR THE SEPARATION OF DRY MATERIALS

Dwight C. Morgan, Jr., and Thomas Hubbard Morgan, Kittanning, Pa., assignor, by mesne assignments, to Morgan Concentrating Company, Wilmington, Del., a corporation of Delaware

Application February 15, 1936, Serial No. 64,078

17 Claims. (Cl. 209—467)

This invention relates to the dry separation of heavier particles from lighter ones, such, for instance, as particles of metal from sand, and pertains to what is generally known in the art as dry flotation.

Heretofore apparatus has been designed to effect the dry flotation of materials. Apparatus of this general type usually comprises a table of some character over which the material to be acted upon is discharged and caused to flow. The table is usually of a perforate character so that air may be blown up through the material as it flows over the table. While apparatus of this general character has been successfully used in some fields as, for instance, in the separation of stone and like materials from coal, we are aware of no apparatus which has been successfully developed for the efficient separation of small metal particles from sand. Many attempts have been made to extract small particles of gold from dry placer sands, but such apparatus as has been developed is cumbersome to use, is not highly efficient, and results in the removal of only a relatively small percentage of the available gold from the sand. Moreover, such machines as have heretofore been devised for this purpose effect only a partial concentration, leaving a relatively large bulk of material which has to be panned to separate the gold from the concentrate. According to the present invention, there is provided a concentrating apparatus and method which can be economically used for the so-called "dry flotation" or "dry extraction" of metallic particles from the sands in which they are carried, such apparatus and method functioning with a high degree of efficiency and resulting in the production of a concentrate in which there is very little sand. The invention provides a concentrating unit of this nature of such character that it may be conveniently mounted on a motor truck or other easily portable structure and operated from a source of power on the truck.

In the dry concentration of materials, such as the separation of gold from placer sands, we have found that during the process of concentration the entire mass of sand passing through the apparatus must be kept in such a state of agitation that the metal particles therein will gravitate to the bottom. After the metal particles have been precipitated to the bottom, their flow, along with the overlying and surrounding body of sand and gravel, should be in a zone of agitation where there is no possibility of the metallic particles being stirred up from the bottom and mixed with the surrounding sand and gravel.

In the present invention, there is provided a separating table having means therein forming flutes or riffles. The flutes or riffles, as well as the entire surface of the bed, are porous to permit the escape of air therethrough from an underlying wind box, whereby air is blown through all of the material passing over the table, and there are no quiescent zones where the particles of heavier materials which have gravitated to the bottom may again be churned up and mixed with the surrounding body of sand and gravel. As stated later herein, the flutes admit a greater amount of air than do other parts of the bed, this being an important feature herein. In the particular form illustrated this is due to the porous bed being thinner in the flutes or riffles than in other parts, so that, as is later stated, more air is admitted through the flutes than through the body of the bed. The invention further contemplates an arrangement wherein the metal particles which are caused to gravitate to the bottom are diverted into a channel having means for trapping the metal or other particles to be recovered while permitting the larger volume of sand or other material to be discarded to pass on.

In its preferred embodiment, the invention further contemplates the provision of some arrangement whereby the contents of the concentrating cups are protected from unauthorized removal. The invention further provides an arrangement wherein the concentrating table is preferably adjustable to any desired inclination whereby it can be adapted to the particular kind of sand or other material being processed to get the best results. The invention further contemplates an arrangement whereby this adjustable table may be kept constantly in a state of vibration during the processing of the material as the combined action of vibrating and air is essential to the most efficient removal of the metallic values.

Our invention may be readily understood by reference to the accompanying drawings, in which:

Figure 1 represents a side elevation of a concentrating unit embodying our invention;

Figure 2 is a transverse vertical section in the plane of line II—II of Figure 1;

Figure 3 is a plan view of a porous concentrating table such as is used in the present invention;

Figure 4 is a plan view of the concentrating table with its side flanges removed and without its supporting frame structure as provided in the machine shown in Figure 1, part of the porous bed of the table being broken away to reveal the underlying structure;

Figure 5 is a fragmentary detail view showing a manner of supporting the porous bed in the frame structure in which it is carried;

Figure 6 is a detail view showing a cushion 5 mounting for the frame in which the porous table is mounted, and which mounting permits of a limited vibration of the table;

Figure 7 is a plan view of a modified form of table;

10 Figure 8 is a transverse fragmentary section in the plane of line VIII—VIII of Figure 7, this view being on a larger scale than Figure 7;

Figure 9 is a side elevation, on a larger scale, of the discharge end of the apparatus showing 15 the collecting cups in which the metals to be recovered are collected;

Figure 10 is a transverse section of Figure 9 on a line between the collecting cups; and

20 Figure 11 is a top plan view of that portion of the machine shown in Figure 9.

In the drawings, 2 designates a supporting frame structure preferably formed of structural steel and of such proportions that it can be conveniently mounted on a motor truck or other mobile structure. Generally, this supporting structure may have a base portion 2a, spaced apart front uprights 2b, and spaced apart rear uprights 2c. Extending along each side of the structure from the top of the uprights 2c to approximately 30 the middle of the uprights 2b are horizontal beams 2d. The front uprights 2b and supporting members 2e provide an elevated support for a hopper 3 having a discharge gate 4 thereon.

Hung from trunnions 5 on the horizontal members 2d is a cradle structure. This cradle structure comprises two depending supports or hangers suspended from the trunnions and designated 6, there being one of these supports at each side of the frame. Each of the supports has secured thereto a longitudinally extending channel member 7. The concentrating table connects the two channels 7 at opposite sides of the frame and it is resiliently mounted on these two channels 7. The concentrating table unit comprises a hollow base structure 8 having side walls 9 (see Fig. 2) with outwardly turned flanges 10. Secured to the top of the flanges 10 are longitudinally extending channel members 11. Welded or otherwise secured to the side walls 9 near the four corners of the table supporting structure are bracket members 12. The bracket members 12 are each provided with a hole 12a therein, the brackets 12 having angular web or gusset plates 12b for giving them the necessary strength. The resilient 55 connection between the bracket members 12 and the channel members 7 is provided through a yieldable medium, preferably a live rubber cushion arrangement. One such arrangement is shown in Figure 6. It comprises a bolt member 60 13 having a cap member 14 at the top and bottom thereof. There is a cushion of live rubber 15 confined between the cap 14 and the top of the channel 7, and a similar cushion of live rubber 15' between the bottom of the channel 7 and the 65 lower cap member 14. The bolt 13 passes through the hole 12a in the bracket 12.

It will be seen that there are four of the brackets 12, one at each corner of the table supporting structure, and there are four of these cushion 70 units for suspending the table supporting structure from the two channel members 7. This manner of suspension for the table supporting structure allows the table supporting structure to be vibrated, but such vibration is cushioned in the live rubber cushions 15 and 15' so that the force

of the vibration is not transmitted to the channels 7 or to the structural frame 2.

Along each side wall of the hollow base member 8 is an angle member 16. In addition to the member 16 there is a supporting lattice 17 (see Fig. 4) formed of intersecting structural members, the angles 16 and the lattice 17 serving to support a porous bed or table 18. The porous bed or table 18 is preferably comprised of a number of separate blocks cemented together to form 10 a monolith. Live rubber, indicated at 19 in Fig. 5, is provided under the porous table where this table rests on the angles 16 or on the lattice. A similar rubber cushion is provided at 20 around the vertical edges of the table 18. The channel members 11 which overhang the table 18 have live rubber under them as indicated at 21. The purpose of so mounting the porous bed on and between the live rubber is that the porous material is of a frangible nature and the live rubber 20 serves to minimize the destructive effect of the 25 vibrating action of the table when the machine is in operation.

In the preferred embodiment of the invention the table 18 has a herringbone arrangement of 25 grooves or channels therein, there being a single longitudinally extending groove or channel 18a and a number of laterally extending inclined branches 18b. All of the branches extend from very closely adjacent the outer edges of the table 30 to the centre trough or channel 18a. Their inclination is toward the lower end of the table.

The supporting member 8 on which the porous bed is carried is not only closed at the sides but is closed at the front and rear, providing in addition 35 to the support for the table, a wind box or chamber. In the rear wall of this supporting structure is an opening having a flange surrounding it to which a flexible air hose 22 is connected. This air hose 22 leads from the discharge end 23 of a 40 blower 24. The blower 24 is designed to deliver a relatively large volume of air at a relatively low pressure to the wind box. It will be noted from Fig. 1 that the depth of the wind box diminishes toward the right as viewed in this figure, thereby 45 causing the volume of the wind box to diminish away from the point where the air enters it. This serves to maintain a substantially uniform pressure of air escaping through the porous material of the bed over substantially the entire area of the bed. If the wind box were of uniform depth, there 50 would be a tendency for the pressure of the air escaping through the table to be greater adjacent the left hand end of the wind box than the right.

The porous bed 18 is retained in place at the right hand end of the structure as viewed in Figures 1 and 4, by a transverse metal strip 25, the top of which is preferably flush with the top of the porous table. Bolted to the end strip 25, as most clearly shown in Figures 9 and 11, is a run-out trough member 26, this trough member being of a depth corresponding substantially to the depth of the groove 18a in the porous table 18 and being in longitudinal alignment with the said central groove. A port is provided in the end strip 25 to enable the material which passes down the groove 18a to flow into the run-out trough 26. The run-out trough 26 is provided with one and preferably two, holes 27 therein. Under each of these holes 27 is a cylindrical cup 28 and 28', these cups preferably being formed of glass and having a relatively thin porous bottom 29. The top of the cup sets in a recess on the under side of the run-out trough, while the bottom of the cup rests on a vertically movable supporting plate 30. The ver-

tically movable supporting plate 30 has an opening under each cup and has a bushing projecting down around each opening, these bushings being designated 31 and 32. The adjustable supporting plate 30 has bushings or sleeves 33 thereon which have a sliding fit on pins 34 depending from the under side of the run-out trough. There is a third pin 35 also extending from the bottom of the run-out trough midway between the two pins 34. This third pin 35, best shown in Figure 10, has a nut 36 at its lower end for confining a compression spring 37, which spring bears against the under side of the adjustable plate 30. Slidable on the upper portion of the pin 35 is a cross arm 38. This arm 38 normally rests on the top of the plate 30 and serves to confine the upper end of a flanged bushing 39 in place.

Pivoted onto each side of the run-out trough by bolts 40 are side plates 41 forming part of a bifurcated lever structure 42, this lever structure having an operating handle 43 and a guard plate structure 44. The two sides are each provided with curved cam slots 41a. Bolts 42a pass through the slots 41a into the cross piece 38 and have a working fit in the slots. The arrangement is such that when the handle 43 is moved upwardly in an arc as indicated by the dotted projection line, the member 38, by reason of the curvature of the slots 41a and the provision of the bolts 42a, will be forced down against the compression of the spring 37, forcing the supporting plate 30 down. When the supporting plate 30 is forced down in this manner, the two cups 28 and 28' can be lifted off the support 30. As long as the handle 43 is maintained at the upper limit of its movement, the plate 30 will stay down and the cups, after being emptied, can be replaced. The handle 43 is then swung back to the position shown in Figure 9. When the handle swings back in this manner the cross member 38 is lifted. This allows the spring 37 to exert an upward pressure on the plate 30, whereupon the plate 30 is lifted up, causing the upper edges of the cups 28 and 28' to be forced into the recesses under the holes 27 provided for the reception thereof.

Leading from the front of the wind box to a position beneath the cup 28 is a pipe 45 having a hand valve 46 therein. The pipe between the valve 46 and coupling 47 below the cup, which coupling is secured to bushing 32, is flexible, preferably being a hose. Leading from the front of the wind box at the opposite side of the run-out trough is a similar air pipe 48 having a hand valve 49 therein and having a terminal portion 50 which is secured to the bushing 31 projecting below the cup 28'. This arrangement provides for air to be blown through the porous bottom of either or both cups selectively, the terminal arrangement between the ends of the pipes and the bushings 31 and 32 on the plate 30 providing for the necessary vertical movement of the plate 30 when it is necessary to remove a re-concentrating cup.

Secured to the front strip 25 above the run-out trough is a sheet metal guard plate 51 which extends over the run-out trough a slight distance above the top thereof. The outer end of this guard member 51 projects under the part 44 of the bifurcated lever arrangement. The arrangement is such that when the lever is in the position shown in Figure 9, it is not possible for an unauthorized person to remove either of the re-concentrating cups or the contents thereof, the first cup being covered by the guard member 51 and the second cup being covered in part by the

outer end of the guard member 51 and in part by the part 44 of the bifurcated lever. Provision is made for locking the lever in place. This comprises the provision of a registering hole in portion 43a with a similar hole in a lug 26a at the end 5 of the run-out trough. The hasp of a padlock A passes through these registering holes and serves to normally lock the reconcentrating arrangement on the run-out trough from being opened or tampered with, except by an authorized person. 10

Secured to the two supporting frame members 2d are bearings 55 for a transverse power shaft 56 for vibrating the bed of the machine. This shaft, the axis of which is parallel to the axis of the trunnions 5, is shown as having a pulley 57 15 at its outer end, but it will be understood that in place of a pulley at 57 a sprocket gear or other gear drive can be positioned anywhere along this shaft. The pulley or other driving means on the shaft 56 is adapted to be coupled to a source of 20 power as, for instance, a source of power driven from the motor vehicle on which the whole unit is mounted. Mounted on the side channels 11, above the concentrating table are bearings 58 for a shaft 59. The shaft 59 where it extends 25 across the bed of the machine, is enclosed in a cylindrical casing or dust shield 60. The shaft 59 is provided at one end with pulleys 61 which are driven through belts 62 from pulleys 63 on the shaft 56. The shaft 59 carries at each end there- 30 of unbalanced weights, such as the unbalanced discs 65. By reason of the size of the pulleys, the shaft 59 is operated at a much higher speed than the shaft 56. The effect of the unbalanced discs or weight 65 on the shaft 59 is to cause the whole 35 concentrating table unit to vibrate, the magnitude of vibration being controlled by the eccentricity or degree of unbalance of the weights 65 and by the degree of resilience of the cushions 15, 15'. The vibration is of relatively high frequency 40 by reason of the high speed of rotation of the shaft 59 under normal conditions of operation. The table, by reason of this arrangement, is caused to vibrate very rapidly during the operation of the machine, but the degree of movement 45 or amplitude of vibration is relatively slight, it being a vibration as distinguished from any appreciable bodily movement of the table.

The shaft 56 is also provided with a pulley which drives a belt 66 to operate the blower 24. 50

By reason of the fact that the table is suspended from the trunnions 5 and the axis of rotation of the shaft 59 coincides with the axis of the trunnions 5, the table structure as a whole can be adjusted to any desired inclination within a 55 limited range in the supporting structure. One simple way of adjusting the angularity of the table from one end toward the other is shown in the drawings where there is shown a hand wheel 67 having oppositely threaded hub portions 68, 60 one of which engages a threaded link 69 suspended from one of the channel members 11. The other hub member 68 engages a similar link member 69' supported on the base of the structure. By turning the hand wheel in one direction or the other, 65 the inclination of the table can be adjusted, the trunnions 5 being the pivoting point for the structure. The upper or left hand end of the table is at all times positioned directly under the discharge gate 4 of the hopper 3. 70

In the operation of the machine, the hopper 3 is loaded with the ore-bearing sand or other material to be processed. The drive shaft 56 is set into operation, causing air to be blown into the wind box beneath the porous table. The air 75

valves to both reconcentrating cups are opened. When the machine has reached its operating speed, the gate 4 is opened to the desired extent. This gate allows the contents of the hopper to pour down onto the upper end of the porous table. The discharge slot in the hopper, as shown in Figure 2, extends substantially the full width of the porous table, so that the material is deposited to a uniform depth across the width of the table. The inclination of the table is set to the desired angle. The rapid vibration of the material together with the blowing of countless small streams of air through it over the entire surface of the bed makes the mass similar to a liquid, any heavier body sinking to the bottom and lighter bodies floating to the top. The material in this state flows just like a stream of liquid down the table to its lower discharge end, the depth being substantially even over the entire table. The particles of greatest specific gravity quickly sink to the bottom and as they move down over the surface of the table they fall into the various herringbone grooves 18b. The inclination of the grooves plus the inclination of the table causes these particles, with the vibration of the table and the current of air coming up through the bottom of the grooves to move toward the central discharge channel 18a on the table. As more air enters the grooves than the surface of the table proper, the material is not only fed along, but the larger amount of air greatly aids in separating metal particles and retaining them in the grooves or riffles. By the time the sand reaches the lower end of the table, the metal particles therein practically all become trapped in the system of grooves or riffles provided in the table. The sand will flow out over the lower edge of the table.

If desired, a conveyor may be located under the discharge end of the table for carrying the sand away to a dump heap or other point of disposal. The metal particles to be recovered along with the overlying and surrounding body of sand pass down the central groove 18a into the run-out trough 26. The run-out trough 26 is a rigid structure, and the vibration of the table is, of course, communicated to the run-out trough. As the sand with the metal particles flows down the run-out trough 26, it passes over the first hole 27. Here the sand is being agitated by vibration and also by air coming up through the bottom of the first collecting cup. The metal particles quickly gravitate to the bottom of the cup, displacing any sand that may have preceded the metal particles into the cup. As the cup gradually fills up with metal particles, the sand is displaced and continues down along the run-out trough over the second collecting cup. Should the first collecting cup be full of metal particles or for some reason should any metal particles escape the first cup, they will be collected in the second cup, provided that at such time the valve 49 for blowing air into the second cup is open. Once the machine is put into operation, ore-bearing sand is continuously fed to the hopper 3 and the material continuously flows over the porous table, the metal particles gradually accumulating in the first receiving cup 28. Sand flowing down the run-out trough and passing both cups eventually flows out the end of the run-out trough onto the waste sand being discharged from the end of the table. When it is observed that the first cup 28 is full of metal particles, the machine is preferably stopped and the cup 28 removed and emptied. If desired, the machine may be run until both cups are full, or, when the first

cup 28 is removed, the second cup which may have a few gold particles but principally full of sand, can be moved up to the position of the first cup. The first cup, after being emptied, is then put in the position previously occupied by the second cup, and this cycle of interchanging of cups repeated.

The cups, although of relatively small capacity, will accommodate metal particles accumulated through quite a long period of time. After several hours of running time, when the cup is removed, it may be partially or practically full of metal particles and partially full of sand. The metal particles are thus collected in a highly concentrated state.

The sand to be processed is preferably screened before being dumped into the hopper 3, or a screen (not shown) may be located below the discharge of the hopper 4, any conventional type of screening apparatus being satisfactory for this purpose. The operator of the machine can readily determine the rate at which the material should be fed to the table and the inclination of the table. He can also control the volume of air supplied to each of the reconcentrating cups. By reason of the fact that the material is evenly diffused across the width of the table, all of the material is aerated to substantially the same degree, whereas if the material were supplied to the table in such manner that it was deeper along one portion of the table than another, such deeper portion would be less effectively aerated and air pressure would be lost on the less heavily covered areas of the table.

The table shown in Figure 3 wherein the grooves are provided in the porous material, constitutes a highly effective form of table. The herringbone arrangement of grooves in effect provides riffles or flutes. At the same time, the thickness of porous material at the bottom of these flutes is less than the thickness of the porous bed between the grooves. This is a desirable feature, because the air permeates to a greater degree through these areas of lesser thickness. This is offset by the fact that there is a greater depth of overlying sand because of the fact that the depth of the sand in the groove is added to the average depth of sand over the entire table. The result is that while there is deeper sand directly over the grooves, there is more air supplied at these points. Instead, however, of providing a plurality of riffles as illustrated in Figure 3, an arrangement such as that shown in Figures 7 and 8 may also be used. In these figures, the porous bed of the machine is designated 70. It is supported over a wind box structure 8 similar to that previously described. The forward end of the table, however, instead of being square, is provided with converging forward edge portions 71. These forward edge portions 71 are provided with a porous lip 72. At the point where the two lips 72 come together there is provided a run-out trough 73. This run-out trough may be provided with reconcentrating cups as heretofore described. With this arrangement, the forward edge of the porous table 70 is supported on an angle bar 74 as shown in Figure 8, and this angle bar is provided with numerous perforations 74a. The lower edge of the porous strip 72 is supported above the angle bar 74, leaving an air space 75. By reason of this arrangement, air will not only flow through the porous bed 70, but will also flow up through the porous edge or riffle 72. This arrangement, therefore, provides a form of porous riffle similar to

that provided by the herring bone grooves of the structure shown in Figures 3 and 4.

In use, where a table having this modified form is employed, the material to be processed is discharged onto the left hand end of the table as viewed in Figure 7. The table is supported in the manner of the table heretofore described, being inclined downwardly toward the pointed end. As the material moves down the table, the table 10 is vibrated and air is blown up through it, causing the precipitation of the heavier particles to the bottom of the mass. The heavier particles gravitate down the table with the overlying and surrounding mass of sand. When the sand 15 encounters the porous bead or riffle 12 at the discharge end of the table, it will flow over the edge and be discharged. The metal particles, however, will be caught against the bottom of the bead or porous strip 12 and be carried down to 20 the run-out trough 13. By reason of the fact that the bead 12 is porous, air will be forced into the sand to keep the heavier particles from being lifted up and churned around by the great overlying mass of sand. We have found that if 25 the strip 12 were of a non-porous nature, the machine would operate with considerably less efficiency.

With machines of this character, a considerable volume of sand must be processed in a short 30 space of time. The content of gold in ordinary dry placer sands averages in most deposits less than $\frac{1}{30}$ of one ounce per 2000 pounds of sand. It is contemplated that the unit shown in the 35 accompanying drawings, being of a width suitable for mounting on an automobile truck, will process the sand at a rate nearly a ton a minute. It will therefore be seen that with this volume of sand passing over the table in a short unit of time, the riffles or other means for trapping the 40 sand must be such that the particles of gold or other metal particles to be recovered, once they come against the base of a riffle, will not be swept along by the continuously flowing stream of sand. It is for this reason that the porous riffle 45 arrangement of the present invention is an important factor in the efficiency of the machine.

The porous bed of the machine may be formed of various commercially available materials of a generally porous character permeable to the 50 flow of air therethrough. Typical materials are bonded silicon carbide grains, natural pumice, mineral filters, and substances of like nature which are porous or permeable to the flow of air or gas, and are less resistant to air flow through 55 the flutes than through other parts of the porous bed.

By the word "air" in our broader claims, we intend to include any gaseous medium which is 60 the equivalent of air under the conditions of this system.

While we have illustrated and described in detail certain specific embodiments of our invention, it will be understood that the drawings are 65 merely for the purpose of illustration and that the invention may be otherwise embodied and that various modifications and changes may be made therein.

We claim:

70 1. A dry concentrating apparatus of the class described, comprising a porous table, and means for forcing air upwardly through said table, the table having flute or riffle portions arranged to contain a greater depth of the material fed than 75 other table portions and cooperating with the air

feed to supply a larger amount of air upwardly through the flute or riffle portions.

2. A table for use in dry concentrating machines, comprising a slab-like member of porous material having open flutes formed therein and means for forcing air upwardly through said table, the flutes and air-forcing means being arranged to supply larger amounts of air to the flutes wherein the feeding material is deeper than upon other table portions. 5

3. In a dry concentrating apparatus, a permeable bed portion having a concentrating flute more permeable than another part of the bed, said flute being arranged to contain thicker or deeper portions of the material feeding over the 15 bed, means for forcing a gaseous medium upwardly through the bed and flute. 10

4. In a dry concentrating apparatus, a permeable bed portion having a concentrating flute more permeable than another part of the bed, 20 said flute being arranged to contain thicker or deeper portions of the material feeding over the bed, means for forcing a gaseous medium upwardly through the bed and flute, and means for vibrating or jarring the bed and flute. 25

5. In a dry concentrating apparatus, a permeable bed having flutes arranged to allow lengthwise travel of dry material, said flutes being arranged to contain deeper portions of the material heated and being more permeable than other 30 parts of the bed, and means for forcing air upwardly through the flutes and bed. 30

6. In a dry concentrating apparatus, a permeable bed having a flute of greater permeability and arranged to be below a greater depth of 35 flowing material than other bed portions, connections arranged to force air upwardly through the bed and flute, and a reconcentrating apparatus to which the bed feeds. 35

7. In a dry concentrating apparatus, a bed 40 which has parts permeable to a gaseous medium, said bed having a plurality of flutes arranged to underlay greater depths of flowing material than other portions of the bed and being of greater permeability to the gaseous medium, the flute 45 system being arranged to feed the dry material forwardly, means for vibrating or jarring the bed, means for forcing air through the bed portion and flute system, and a re-concentrator to which the material is fed from said concentrating 50 table. 50

8. In dry concentrating apparatus, a stratifying table having pervious portions at a general level and pervious groove portions into which the concentrates sink, and means for feeding a gaseous fluid upwardly through the table and groove 55 portions, the groove portions and gaseous feed being arranged to supply greater amounts of air through the groove portions than through other table portions. 60

9. In dry concentrating apparatus, an inclined stratifying table having pervious portions at a general level and pervious groove portions into which the concentrates sink, and means for feeding a gaseous fluid upwardly through the table 65 and groove portions, the groove portions and gaseous feed being arranged to supply greater amounts of air through the groove portions than through other table portions. 65

10. In dry concentrating apparatus, a stratifying table having pervious portions at a general level and pervious groove portions into which the concentrates sink, and controllable means for feeding a gaseous fluid upwardly through the table and groove portions, the groove portions and 75

gaseous feed being arranged to supply greater amounts of air through the groove portions than through other table portions.

11. In the dry concentration of material having heavier and lighter particles, the steps consisting of feeding the material over a permeable stratifying table causing the concentrates to sink into permeable grooves of the table beneath lighter portions of the material, and feeding a gaseous fluid in greater amount upwardly through the grooves and in lesser amount through other table portions.

12. In the dry concentration of material having heavier and lighter particles, the steps consisting of feeding the material over a permeable inclined stratifying table causing the concentrates to sink into permeable grooves of the table beneath lighter portions of the material, and feeding a gaseous fluid in greater amount upwardly through the grooves and in lesser amount through other table portions.

13. In the dry concentration of material having heavier and lighter particles, the steps consisting of feeding the material over a permeable stratifying table causing the concentrates to sink into permeable grooves of the table beneath lighter portions of the material, and feeding a gaseous fluid in greater amount upwardly through the grooves and in lesser amount through other table portions, and vibrating the table.

14. A dry concentrating apparatus of the class described comprising a pervious table, means for vibrating the table, and means for forcing a gaseous medium upwardly through said table, the table having flute or riffle portions arranged to contain a greater depth of the material fed than other table portions and cooperating with the gaseous feed to supply a larger amount of said

gaseous medium upwardly through the flute or riffle portions.

15. A dry concentrating apparatus of the class described comprising a pervious table inclined from a receiving end portion downwardly toward a discharging end portion, means for vibrating the table, and means for forcing a gaseous medium upwardly through said table, the table having flute or riffle portions arranged to contain a greater depth of the material fed than other table portions and cooperating with the gaseous feed to supply a larger amount of said gaseous medium upwardly through the flute or riffle portions.

16. In the method of dry concentration of the heavier particles in a dry mixture, the steps consisting of feeding the mixture forwardly over a pervious table having a flute or riffle portion arranged transverse to the forward movement of the mixture and containing a greater depth of the mixture than other table portions, agitating the mixture, forcing air upwardly through the table and causing a greater feed of air through the flute or riffle portion than through other table portions.

17. A dry concentrating apparatus of the class described comprising a porous table, means for forcing air upwardly through said table, said table having flute or riffle portions therein below a plane representing a surface level of said table, said flute or riffle portions being arranged to contain a greater depth of material fed than other table portions, said air means cooperating with said table and said portions thereof to supply air through the upper and lower table portions, with a larger amount of air upwardly through said flute portions than through other portions of the table.
